UNITED STATES PATENT OFFICE.

WILLIAM ENGEL, OF NEW YORK, N. Y., ASSIGNOR TO A. L. PHILLIPS & CO.,
OF SAME PLACE.

DESIGN FOR AN ORNAMENT FOR CLOAKS AND OTHER GARMENTS.

SPECIFICATION forming part of Design No. 14,005, dated June 26, 1883.

Application filed April 26, 1883. Term of patent 3½ years.

To all whom it may concern:

Be it known that I, WILLIAM ENGEL, a citizen of the United States, residing in the city, county, and State of New York, have invented and produced a new and original Design for an Ornament for Cloaks and other Garments, of which the following is a specification, reference being had to the accompanying drawing, forming part thereof, in which my newly-de-
10 signed ornament for cloaks and other garments is shown.

My invention consists in a rosette made in imitation of the face of an owl.

On a rosette, A, a mold, B, is secured, and
15 at each side of one end of the same a smaller rosette, C, is fastened on the rosette A, which

rosettes C are each provided with a central bead, D. The mold B represents the bill of the bird, and the rosettes C the eyes. From each rosette C a loop, E, projects, which is 20 fastened on the rosette A. The loops E project outward and from each other, and represent the ears of the bird.

The rosette is to be used for ornamenting cloaks, dresses, and other ladies' garments. 25

I claim—

The herein-described design for a rosette, consisting of an owl's face, as set forth.

WILLIAM ENGEL.
